(57) **CLAIM**

The ornamental design for a pupilometer, as shown and described.

DESCRIPTION

FIG. 1 is a top view of a pupilometer, showing my new design;

FIG. 2 is a bottom view thereof;

FIG. 3 is a left side view thereof;

FIG. 4 is a right side view thereof;

FIG. 5 is a front view thereof;

FIG. 6 is a rear view thereof; and,

FIG. 7 is a perspective view thereof.

The broken line showing portions of a pupilometer is included for the purpose of illustrating environmental structure and forms no part of the claimed design.
